UNITED STATES PATENT OFFICE

FRED P. ANGELL, OF BATTLE CREEK, MICHIGAN

FLUSH VALVE

Application filed February 7, 1927. Serial No. 166,459.

The objects of this invention are:

First, to provide such a structure which is a simple and effective high speed device that is economical to produce.

Second, to produce such a structure in which there are improved auxiliary storage supply and suction means to secure prompt full action, and incidentally to prevent water hammer.

Third, to provide an improved construction of toilet bowl refill means for such a flush valve structure.

Objects pertaining to details and economies of construction and operation will appear from the detailed description to follow. The invention is clearly defined in the claims.

A structure which is a preferred embodiment of the invention is illustrated in the accompanying drawing, in which:

Fig. 1 is a diagrammatic view of my flush valve and auxiliary supply and cushioning means connected to a water closet bowl.

Fig. 2 is an enlarged detail vertical sectional elevation view taken on line 2—2 of Fig. 3.

Fig. 3 is a detail transverse horizontal section taken on line 3—3 of Fig. 2, the delivery coupling being shown in full lines.

Fig. 4 is a detail sectional elevation view through the valve and its plunger taken on line 4—4 of Figs. 2 and 3.

Fig. 5 is a detail inverted sectional plan taken on line 5—5 of Fig. 4, with the guiding lugs for the valve in full lines.

The parts of the drawing will be identified by their numerals which are the same in all views.

1 is a closet bowl. 2 is my improved valve casing. 3 is the delivery coupling from the flush valve to the closet. 4 is the supply pipe. 5 is the auxiliary storage supply and cushion cylinder, and 6 is the connection for the pipes and elbow to the flush valve, the same connecting through a reduction coupling 61 and 45 coupling nut 62.

7 is the valve having a rubber face 71 and is provided with a central bore 72 in the lower part and a reduced bore 73 in the upper part, and a cross bore 74 in which is an adjustable screw choke valve 75 for restricting the passage. 77 is the cross bore for the refill valve structure. 78 is the refill valve plug which has a collar or head 78' fitting loosely in the bore, and a light spring 78'' tends to hold valve 78 open at a light pressure. The valve seat 77' is of about the diameter of the valve plug 78. A plug 8 closes the end of the bore 77 and provides a stop for the valve plug 78 in its open position.

9 is the cylindrical flush valve chamber. 10 is the hydraulic cup packing which reciprocates as a piston in the same and is connected to the upper part of the valve body 7, and reciprocates as a plunger in the pressure chamber 9.

A central coiled spring 11 tends to hold the valve 7 seated. The manually operated release valve 12 controls the passage into the spillway chamber 91 from pressure chamber 9. This is operated by a push pin 13 having a button 131 held normally outward by the spring 132. 134 is the valve casing having a lateral port 135 which opens into the spillway chamber 91. The area of the passage controlled by the valve 12 is much in excess of the area of the choked bore 73 in the valve 7.

The auxiliary supply and storage chamber or cylinder and water cushion are comprised in the casing 5 in which there is disposed a plunger 51 with hydraulic cup packing. The plunger 51 moves against a group of coiled springs 52 which abut on the head 54. This auxiliary supply chamber can be disposed in any convenient place between floors, entirely concealed, and yet it does its work effectively and provides an auxiliary storage supply for a large initial volume of flow which insures prompt and complete flushing. Incidentally it also prevents the water hammer which

often occurs with flush valves. My valve will operate with any auxiliary supply if of sufficient size and pressure. For the usual size of water closet bowl, a vertical three inch pipe with closed upper end, to provide an air cushion, six feet in length is sufficient.

Having described the various parts of my invention, I will now indicate their operation.

10 When the release valve 12 is opened, water confined in the pressure chamber 9 is free to flow through the port 135 into the spillway chamber 91 under urge of the hydraulic cup 10 carried by the valve 7. The valve 7 and its face 71 is raised from its seat by the pressure of the water thereon, the spring 12 being insufficiently strong to resist the pressure of the water confined in the auxiliary supply chamber 5. The water rushes by the valve 7 and through the spillway chamber 91 through the piping 3 into the closet bowl where the usual flushing takes place. When the manual pressure on the valve 12 is released, various reactions take place. Water 25 passes through the central bore 72 and through the choked bore 73, gradually filling the pressure chamber 9, the spring 12 meanwhile having forced the valve 7 and its face 71 onto its seat as the pressure has been released. When the pressure chamber 9 becomes filled, pressure gradually is built up and acts upon the hydraulic cup 10, the bottom of the face 71, the back of the collar 78' on the valve plug 78 and the front of the collar 78' of the plug 78. As this pressure gradually increases, the valve plug 78 is forced to its seat 77' by a force equal to the difference between the combined pressure of the spring 78'' plus the pressure on the front of the collar 78' and the pressure at the back of the collar 78' reacting in the bore in front of the plug 8.

As the area of the hydraulic cup 10 is greater than the area of the valve face 71, the difference in areas under the same pressure holds the valve firmly against its seat and assures a tight seal.

It can be seen that the full reaction of the pressure of the water on the valve plug 78 cannot take place until the pressure chamber 9 is completely filled, and that the pressure chamber 9 fills at a predetermined rate depending on adjustment of the choke 75 in the bore 73. By this means the length of time 55 water will flow past the valve plug 78 and into the spillway 91 after the valve 7 and its face 71 has become seated, and consequently the volume of water, may be accurately determined to compensate for various water supply pressure. The pressure, of course, is gradually increased during the whole closing period due to the filling of the auxiliary chamber under increasing pressure, due to the yielding cushion action of that device. 60 The pressure increase continues after the

final closing of the valve. This is important, as, in the modern toilet bowl, most of the water and refuse is siphoned out of the trap and it is necessary to maintain a water seal in the trap. That is to say, the refill is required.

I have described my invention in the details which I prefer. I desire to state that the valve parts can be used with other auxiliary supply and cushioning means and the cushioning means are available in other relations. I desire to claim invention specifically as well as broadly as pointed out in the appended claims.

Having thus described my invention, what I claim as new and desire to secure by Letters Patent is:

1. In a flush valve structure, the combination of a suitable casing with central cylindrical chamber, a plunger valve having a rubber face therein of smaller diameter than the plunger adapted to reciprocate in the said cylinder chamber, a central large axial bore through the bottom of said valve and a restricted axial bore at the top thereof for permitting the inflow of water to the central cylindrical chamber to seat the valve, a cross bore in said valve with a plug valve with spring holding it slightly open to be closed after the closing of the main valve by the action of water passing around the valve plug and the accumulation of pressure back of it, and an auxiliary supply chamber and cushion device comprising a cylinder with spring pressed plunger therein interposed in the supply adjacent said valve, as described.

2. In a flush valve structure, the combination of a suitable casing with central cylindrical chamber, a plunger valve having a rubber face therein of smaller diameter than the plunger adapted to reciprocate in the said cylinder chamber, a central large axial bore through the bottom of said valve and a restricted axial bore at the top thereof for permitting the inflow of water to the central cylindrical chamber to seat the valve, a cross bore in said valve with a plug valve with spring holding it slightly open to be closed after the closing of the main valve by the action of water passing around the valve plug and the accumulation of pressure back of it, and an auxiliary supply chamber and cushion device interposed in the supply adjacent said valve, as described.

3. In a flush valve structure, the combination of a suitable casing with central cylindrical chamber, a plunger valve having a rubber face therein of smaller diameter than the plunger adapted to reciprocate in the said cylinder chamber, a central large axial bore through the bottom of said valve and a restricted axial bore at the top thereof for permitting the inflow of water to the central cylindrical chamber to seat the valve, and a cross bore in said valve with a plug valve

with spring holding it slightly open to be closed after the closing of the main valve by the action of water passing the valve plug and the accumulation of pressure back of it, as described.

5 4. In a flush valve structure, a plunger valve with automatic closing means, in combination with an auxiliary supply and storage chamber and cushion device comprising a cylinder with spring pressed plunger therein interposed in the supply adjacent said valve, as described.

10 In witness whereof I have hereunto set my hand.
